UNITED STATES PATENT OFFICE.

JOHN A. REED, OF NEW YORK, N. Y.

STEAM-ENGINE VALVE.

Specification of Letters Patent No. 12,873, dated May 15, 1855.

To all whom it may concern:

Be it known that I, JOHN A. REED, of the city and county of New York, have invented a new and useful Improvement in Valves for Steam-Engines, Applicable to Any Steam-Engine, but More particularly to Locomotive Steam-Engines; and I do hereby declare that the following is a full and exact description of the manner of constructing the same, reference being made to the accompanying drawing, wherein—

Figure 1, is a plan of a steam cylinder *a*, with the steam passage *r*, and the exhaust passage *t*, the head of the cylinder *u*, the valve rod *y*; the valve in place *z*, *z*, secured to the rod, which passes through a stuffing box *A*³. One end of the rod rests in a button *v*; the other end of the rod being supported in a lug *A*⁹. *e*, is an arm which operates the valve by means of the stop *A*⁴ and *A*⁶, each faced with a washer *a*⁵ and *a*⁷, the air chamber *m*, the ejection aperture *h*, and the head of the water cylinder *o*, the frame *b*' of the cylinder *a*, and the cylinder *h* is cast with the cylinder and form a part thereof.

Fig. 2, is a longitudinal section through the line A, B, showing the steam passage *r* the valve rod *y*, the steam port or passage *b*², *b*², the valve *z*, *z*, the stop *a*⁴ and *a*⁶, the lugs *v*, *a*⁹, the piston *b*, piston rod *c*, working through a stuffing box *d*, an arm *e*, which operates the valve by means of the stop, each stop faced with india rubber or leather *a*⁵, *a*⁷. The piston rod *c*, working through a second stuffing box *f*, is attached to a piston head *a*⁸. The cylinder *h* is inclosed by a casing of metal *g*, which, with the cylinder forms a water passage *i*, the suction pipe being shown at *a*⁹₁, the ejection pipe at *h*, the valves *n*, *n*, *n*, *n*.

Fig. 3, is the end of the steam cylinder *a*, and valve seat *a*', *a*². Fig. 4 is the end of the water cylinder *h*, with the valve seat *p*. Fig. 5, is a view of a water valve *n*. The same letters refer to like parts.

To enable others skilled in the art to which my invention appertains to construct the same, I construct a cylinder of iron *a*, which is to be bored to a regular diameter and to be inclosed at each end in the usual manner of securing and packing the heads of a steam cylinder, the piston *b*, is to be properly secured to a piston rod *c*, which is to operate through a stuffing box *d*, let into the head of the steam cylinder in the

usual way; upon the piston rod is an arm *e*, properly secured; the piston rod beyond the arm passing through a second stuffing box *f*, let into the iron casing *g*, and the water cylinder *h*; the water cylinder is to be constructed in the usual way of iron, and bored to a regular diameter, with a passage between the cylinder and metal casing *i*, sufficient for the admission of the water which is to fill the cylinder, and is to be ejected at the aperture *h*. Situate immediately beneath the air chamber *m*; the water valves *n*, *n*, *n*, *n*, are shown in place and are semi-circular in shape, each being secured properly to permit the free admission and emission of the water; either head *o*, *o*, of the water cylinder being open with diagonal arms or braces *p*, *p*, *p*, *p*, to keep the water valves in place, and which may be secured against the arms, which are constructed of a brass plate in any way most convenient. The steam passage *r*, is shown upon the upper side of the steam cylinder with the injection *s*, and exhaust *t*, passages, and also the steam port or passage *b*², *b*², attached to the head *u*, of the steam cylinder is a button *v*, which is let into the cylinder head *w*, and into which is inserted an end *x*, of the valve rod *y*, the face of the button forming one side of the exhaust passage *t*.

The valve *z*, is constructed of brass of a cylindrical shape as shown, the face being turned truly, one face *a*' operates as the injection; and the opposite face *a*², as the exhaust or ejection face, for the admission and exhaust of the steam when the engine is in operation; or the valves may be constructed of a double cone each face being turned truly and arranged to fit the valve seat; a stuffing box *a*⁸ is screwed into the cylinder head through which the valve rod passes; a metal stop *a*⁴ is secured to the valve rod with an india rubber or leather washer *a*⁵ and which will give elasticity to the stop when the arm is set in motion to operate the valve rod, the rod passes through a slot in the arm *e*, and beyond the arm is a second metal stop *a*⁶ with a like india rubber or leather washer *a*⁷, for a like purpose as *a*⁵, that is to give elasticity to the stop when the arm is set in motion to operate the valve rod—the end of the valve rod resting in a lug *a*⁹ in the casing of the water cylinder, the reciprocating motion of the piston rod operating the valves *z*, *z*, to admit and exhaust the steam to and from

the cylinder, the operation of which sets in motion the piston a^8 of the water cylinder, which is successively filled and emptied by means of the water valves n , which may be 5 made of india rubber or leather; the water entering at the aperture $a^9\frac{1}{2}$, upon the lower side of the cylinder and being ejected at k . I have not considered it essential to give the dimensions for constructing the cylinders, piston rods, stuffing boxes, or any of 10 the parts described, because any person ordinarily skilled in the art of constructing steam and water machinery will have a knowledge of the necessary dimensions; it 15 is requisite, however, to say that I consider it better to construct the piston rod of copper because that metal will not rust the valve rod of iron, the valves of brass, and the stops of iron. The air chamber should 20 be properly secured to the casing g , and at its greatest diameter should be equal to the diameter of the cylinder.

I have said that my improved valve is applicable to the steam engine; but more 25 particularly to the locomotive steam engine. My reason is because of its simplicity and ease of management, being opened and closed by the motion of the piston rod, or 30 by the cross head, and previous to the piston rod having reached the end of the stroke giving a lead to the steam to overcome the inertia of the piston and connecting rods, causing the crank to work more

regular, and dispensing with eccentrics and 35 rocking shaft; the pressure upon the valve 40 from the steam pipe being nearly balanced, it requires but a small amount of pressure to operate the valve.

I have added a water cylinder and the 45 necessary apparatus to operate the same in connection with the valve rod and valve, with a view to show the simplicity of my invention, and its applicability in forcing water as an engine. No part of the water apparatus however is claimed.

What I do claim as new and desire to secure by Letters Patent is—

Beveling the edges of the cylindrical valve, or its equivalent, and beveling the edges of the steam ports, whereby I am enabled to move the valves within the ports; the beveled edges of the ports, thus being 50 valve seats, and the beveled edges of the valves being faces to fit thereto, as herein set forth.

In witness whereof I have hereunto subscribed my name this sixth day of April in the year of our Lord one thousand eight hundred and fifty five, at the city and county of New York in the State of New 55 York.

JOHN A. REED.
